UNITED STATES PATENT OFFICE

JOHN T. COSGROVE, OF KANSAS CITY, MISSOURI

PULLER

Application filed May 4, 1931. Serial No. 535,016.

This invention relates to tools, and particularly apparatus adapted for use in connection with imparting an instantaneous impelling force to work of a nature which precludes the use of ordinary hammers or similar instruments.

The primary object of the instant invention is to provide a mechanic's tool in the form of a puller especially constructed for use in extracting automobile axles where the same require an exceptional amount of force to dislodge them from the housing and other related parts.

An even further object of this invention is the contemplation of a puller having a novel combination of parts which coact to form an effective tool which might be utilized in connection with imparting a force to most any kind of work.

Minor objects of the invention will appear during the course of the detailed specification, referring to the accompanying drawing, wherein:

Figure 1 is a side elevation of a tool in the form of an axle puller embodying the present invention.

Fig. 2 is a perspective view of the same, on an enlarged scale, and with the slidable weight entirely removed from the apparatus.

Fig. 3 is a still further enlarged vertical, fragmentary, sectional view through the removable head of the puller and showing the same associated with an axle.

Fig. 4 is a vertical cross section through the rod, taken on line IV—IV of Fig. 1, and,

Fig. 5 is a perspective view of a modified form of rod which might be utilized, when using the tool for purposes other than pulling an axle.

Figs. 1 to 4 inclusive of the drawing illustrate a puller constructed in accordance with the preferred form of the invention. A tool embodying the features contemplated is well adapted for use when it is desired to dislodge an axle. Since the necessary force cannot be imparted to this automobile part through the ordinary means, it is advisable always to employ apparatus as illustrated.

Like reference characters designate similar parts in Figs. 1 to 4 inclusive, and the nu-

meral 8 designates a novelly constructed head, the wall 10 of which is formed to present a wedge-shaped notch 12 which engages the work as hereinafter set down. Wall 10 connects sides 14 of the U-shaped portion of head 55 8 and the base of this portion, indicated by the numeral 16, is provided with a hole 18 therethrough to receive one end of rod 20. This end of rod 20 is threaded as at 22 to receive nut 24, after rod 20 has been passed 60 through hole 18. The opposite end of rod 20 has formed thereon a stop 26 and a weight 28 is slidably supported by rod 20 between head 8 and stop 26.

Weight 28 has enlarged ends 30 to directly 65 engage stop 26 and base 16 of head 8 to stop its movement along rod 20. A longitudinal bore 31 is cast through weight 28 which slips over rod 20 when the apparatus is assembled. In practice, notch 12 fits over the work to be 70 engaged and where the puller is used in connection with an axle 32, notch 12 fits over the threaded portion 34 thereof and behind nut 36.

In practice, also, it is necessary to remove 75 the wheel of the automobile before the puller is attached to axle 32. After the wheel-removing operation, nut 36 is replaced and moved far enough along threaded portion 34 to insure a positive grip and yet preclude 80 stripping.

It is important that wall 10 be of material which springs sufficiently to keep the head from breaking when weight 28 is moved 85 along rod 20 against stop 26 in the direction of the arrow shown in Fig. 1. In the manufacture of head 8, this wall 10 may be welded to sides 14 or otherwise affixed after notch 12 is cut and the material forming wall 10 is treated as desired.

The modified showing of a part of this apparatus illustrated in Fig. 5 renders clear a manner in which the puller might be used for purposes other than an axle puller. In 95 this instance rod 100 has a stop 102 rigid with one end thereof, while a hook 114 is formed at the opposite end of rod 100. In this showing there is no weight mounted upon rod 100, but the combination illustrated in 100

Fig. 1 is precisely the same and further comment is unnecessary.

The operation of this pulling apparatus, while made clear during the foregoing specification, might be emphasized by stating that an enormous force is applied to axle 32 longitudinally thereof when weight 28 is rapidly moved against stop 26. The sudden jerk is imparted directly to axle 32 and 10 since notch 12 is in longitudinal alinement with rod 20, there are no lateral strains to break a direct force. The varying width of notch 12 obviously permits head 8 to engage axles of various diameter and while the form 15 of head 8 illustrated is preferred, it must be understood that modifications as to specific structure might be made without altering the effectiveness of the puller.

Having thus described the invention, what 20 is claimed as new and desired to be secured by Letters Patent is:

1. A puller comprising a rod; a weight slidably supported thereby; and a head formed on each end respectively of said rod; 25 one of said heads formed to engage the work and including a U-shaped body, said rod slidably and rotatably engaging the base of said body, and a notched wall extending between the ends of said U-shaped body, said notch 30 being in longitudinal alignment with said rod, said notched wall being resilient, whereby to flex and absorb destructive shocks when the puller is in use.

2. A puller comprising a rod; a stop integral with the rod at one end thereof; a threaded portion at the other end of said rod; a U-shaped body having a hole through the base thereof, said rod slidably engaging said body by passing through said hole whereby 40 to project the threaded portion between the sides of said U-shaped body; a nut on the threaded portion of said rod to limit the sliding movement thereof in one direction; a weight slidably supported by the rod intermediate the head and U-shaped body; and a work engaging wall joining the ends of said body sides said wall being resilient and adapted to flex to absorb destructive shocks when the puller is being operated.

3. A puller comprising a rod; a stop integral with the rod at one end thereof; a threaded portion at the other end of said rod; a nut on the threaded portion of said rod; a weight slidably carried by the rod intermediate the stop and nut; and a work-engaging head mounted on the rod at the threaded end thereof, said head having a U-shaped body having walls of uniform thickness throughout, a hole formed through the base of said body of a diameter greater than the diameter of said rod, the rod passing through said hole to project the said nut within the walls of said body whereby to permit free rotation without longitudinal movement along the rod, and a resilient work-

engaging wall joining the ends of said U-shaped body walls, said resilient wall being adapted to spring sufficiently to absorb destructive shocks when the puller is in use.

In testimony whereof, I hereunto affix my signature.

JOHN T. COSGROVE.
